UNITED STATES PATENT OFFICE.

ALFRED SCHICKERLING, OF SCARSDALE, NEW YORK.

CONTAINER FOR CARDS, SLIPS, ETC.

Application filed September 3, 1921. Serial No. 498,435.

To all whom it may concern:

Be it known that I, ALFRED SCHICKERLING, a citizen of the United States, and a resident of Scarsdale, county of Westchester, and State of New York, have invented certain new and useful Improvements in Containers for Cards, Slips, Etc., of which the following is a specification.

My invention is designed to afford, as an article of manufacture, a simple, but convenient and effective holder or receptacle for an identification card, a lodge or fraternity card or certificate, an individual pass or passport, or in fact any analogous foldable sheet or document which it is desired to carry upon the person for ready reference; and to this end the invention consists in the specific construction, combination, and arrangement of parts herein described and claimed, whereby a flexible memorandum slip of suitable character may be installed in the container or removed therefrom, or exposed for inspection without detachment therefrom, with facility, while at the same time affording means whereby said slip may be adequately isolated and protected when not required for immediate use, all as hereinafter fully set forth.

In the accompanying drawings, Fig. 1, is an elevation, on an enlarged scale, of the main parts of my device, separated;

Fig. 2, is a central longitudinal section of the slip-spool, closed;

Figs. 3 and 4, are central longitudinal sections of the structural parts of said slip-spool, separated;

Fig. 5, is a transverse section, on a still larger scale, of the slip-spool taken upon plane of line 5—5, Fig. 2, with a flexible slip wound therearound,—the outer tubular envelope being indicated in dotted lines;

Fig. 6, is a view of the slip-spool opened up to show the slip holding means, and a foldable slip arranged therein for inner face inspection;

Fig. 7, is a side end elevation of the slip-spool on an enlarged scale, to more clearly show the snap lock construction;

Fig. 8, is an inner end elevation of the slip-spool;

Fig. 9, is a side elevation of the slip-spool closed upon a folded slip arranged for inner face inspection, as in Fig. 6;

Fig. 10, is a similar view showing the

folded strip arranged for external face inspection;

Fig. 11, is an elevation of the slip-spool, opened up;

Fig. 12, is an elevation of the complete device, the slip-spool being positioned in the barrel or envelope.

By the term "slip" as hereinafter used in the specification and claims, I mean to designate any strip of flexible material suitable for the purposes set forth, and having imposed on one or both surfaces datum, or memoranda, either printed or otherwise, as may be found most expedient, which it is desirable to carry upon the person in a conveniently accessible manner, for purposes of identification, for reference, or for analogous uses or reasons, as for instance, passport, certificate of membership, or other individual exhibit or proof.

The tubular shell or casing C, is preferably, (although not necessarily) of cylindrical form, closed permanently at one extremity, at which it is formed with a loop c, or equivalent device, for attachment to a watch or similar chain, or like means of suspension upon the person, if desired, although the container in a unitary sense, may be made small enough to fit in a vest or other garment pocket.—Fig. 12, representing the approximate size as designed for the accommodation of a lodge card or certificate, etc. The other extremity of the tube C, is formed with a mouth or inlet c', the edge of which is formed with an annular shoulder c², for engagement with a spring clip-cap s, on the outer extremity of the slip-spool S.

The inner end of the slip-spool S, is coupled to the container tube C, by means of a flexible ligament f, consisting preferably of a chain of suitable length and thickness (exaggerated somewhat in Fig. 1, for convenience of illustration) attached at one extremity to the inner closed end of the tubular casing C, as shown in dotted lines in Fig. 1, and swivel-connected at the other extremity to a ball-stud s', or equivalent, on the inner end of the spine s², of the slip-spool S, as shown in the aforesaid Fig. 1, of the drawings, this form of ball-stud connection providing for the swivelling of the chain by simple means which admit of the rotation of the slip-spool S, for the purpose of winding or unwinding the exhibit slip e, thereon.

The slip-spool S, consists of a main portion or spine s^2 , to the outer extremity of which the spring-clip cap s , is secured. When made of elastic resilient metal the 5 cap s , (in order to avoid the use of a degree of heat that might impair the elasticity of the resilient or snap edges of the cap) is soft soldered to a filler or base plate s^* , which is hard soldered to the outer end of the spine 10 s^2 , as indicated more particularly in Fig. 2, of the drawings.

Pivottally attached to the spine s^2 , at s^3 , is a clamping member s^4 , foldable over the spine s^2 , as shown in Figs. 1, 2, 5, 7, 8, 9 15 and 10, for the purpose of holding the medial portion of a flexible slip e , such as hereinbefore designated, and as indicated in Figs. 2, 5, 6, 9 and 10. The clamp s^4 , is held in closed relationship with the spine 20 s^2 , by spring-snap engagement of the inner ends of the two said parts s^2 , s^4 , as indicated more particularly in Figs. 1, 7 and 8, one part, the spine s^2 , as shown in the drawings, being made with overlapping snap tongues 25 s^5 , s^6 , for contractual engagement with inclined surfaces s^6 , s^6 , on the other part, s^4 , although obviously an alternative arrangement might be resorted to with like effect, in that the snap tongues s^5 , s^6 , might form 30 part of the clamp s^4 , and the inclined surfaces s^6 , s^6 , might be formed on the spine s^2 ; or in fact any equivalent snap fastening between the parts might be resorted to without departing from the spirit and intent of 35 my invention in this respect.

In order to more effectually hold the insert slip e , against movement on or within the spool S, I form both the spine s^2 , and the clamp s^4 , with inturned bearing tongues 40 s^8 , s^9 , preferably struck up out of the material of which the parts are formed, as indicated more particularly in Figs. 2, 3 and 4, of the drawings, although this is not an essential feature of my invention.

In this connection it may be stated that I do not limit myself to the use of metal in the formation of my slip holder and container, since vulcanized rubber or other suitable material might be used for the purpose; 50 neither do I limit myself to the identical form and construction of parts shown in the drawings by way of exemplification, since variations and modifications in minor details may be resorted to without evading the spirit and intent of my invention.

The slip e , may be folded and clamped to and within the spool S, so as to be read either internally or externally, as, for instance in Fig. 6, it is shown as folded for 60 internal reading, in which case the spool S, has to be opened for the purpose, whereas in Fig. 10, it is shown as folded for external reading, in which case it is not necessary to open the spool for the purpose. In either 65 case the slip e , may be wound around the

spool S, for insertion in the tubular container C, as indicated in Fig. 5.

I have herein shown the tubular casing C, as of tubular cylindrical configuration, although a tubular casing of other than circular form in cross section may obviously be used if preferred, in which case the spring cap s , would of course be made to conform thereto.

What I claim as my invention and desire 75 to secure by Letters Patent is,

1. A container of the character designated, comprising a tubular casing, and a slip-spool of pivoted interlocking sections 80 removably insertable therein and formed with means for clamping a slip of flexible material, for the purpose set forth.

2. A container of the character designated, comprising a tubular casing, a slip-spool of pivoted interlocking sections 85 removably insertable therein, a flexible ligament connecting the casing and spool, and means upon the slip-spool for clamping a slip of flexible material thereto, for the purpose described.

3. A container of the character designated, comprising a tubular casing, a slip-spool removably insertable therein, said spool being formed of hinged interlocking sections, a flexible ligament swivel-connecting 95 the casing and spool, and means upon the slip-spool for clamping a slip of flexible material thereto, for the purpose described.

4. A container of the character designated, comprising a tubular casing, a slip-spool of pivoted interlocking sections 100 removably insertable therein, and a spring-clip cover for closing the otherwise open end of said tubular casing, substantially as set forth.

5. A container of the character designated, comprising a tubular casing, a slip-spool of pivoted interlocking sections 105 removably insertable therein, a flexible ligament connecting said casing and spool, and a spring-clip cover for closing the otherwise open end of said tubular casing, for the purpose described.

6. A container of the character designated, comprising a tubular casing, a slip-spool of pivoted interlocking sections 110 removably insertable therein, means upon said slip-spool for clamping a slip of flexible material thereto, a flexible ligament connecting said casing and spool, and a spring clip 115 cover for closing the otherwise open end of said tubular casing, substantially in the manner and for the purpose described.

7. A container of the character designated, comprising a tubular casing, and a slip-spool removably insertable therein, said slip-spool consisting of a spine member and a clamping member articulately connected therewith, substantially in the manner and 125 for the purpose described.

8. A container of the character designated, comprising a tubular casing, and a slip-spool removably insertable therein, said slip-spool consisting of a spine member and a clamping member articulately connected therewith, said spine and said clamp being formed with inturned bearing tongues, substantially in the manner and for the purpose described.
- 5 9. A container of the character designated, comprising a tubular casing, and a slip-spool removably insertable therein, said slip-spool consisting of a spine member and a clamping member articulately connected therewith, said spine and said clamp being formed with inturned bearing tongues, substantially in the manner and for the purpose described.
- 10 9. A container of the character designated, comprising a tubular casing, and a

slip-spool removably insertable therein, said slip-spool consisting of a spine member and a clamping member articulately connected therewith, said spine and said clamp being 15 formed with inturned bearing tongues, substantially in the manner and for the purpose described.

ALFRED SCHICKERLING.
